UNITED STATES PATENT OFFICE.

CHARLES C. MOSHER, OF SENECA FALLS, NEW YORK.

ATTACHING WINDOW-SHADES TO ROLLERS.

SPECIFICATION forming part of Letters Patent No. 248,494, dated October 18, 1881.

Application filed February 4, 1880.

To all whom it may concern:

Be it known that I, CHARLES C. MOSHER, of Seneca Falls, in the county of Seneca and State of New York, have invented a new and useful Improvement in Bands for Attaching Window Shades and Curtains to Rollers, whether the same are provided with springs or not, of which the following is a specification.

10 The object of my invention is to provide a better method of attaching and adjusting shades and curtains to rollers, upon which they hang without using nails, tacks, or glue. Heretofore shades have been attached to the 15 rollers by cut rings, first placed in grooves upon the rollers, and then the ends of the curtains or shades slipped under one end of each ring, one at a time. This method is objectionable, because the end of the rings have to bear 20 with such pressure on one end of the shade or curtain so fastened as to penetrate and thus injure it. The curtain is with difficulty adjusted so as to hang true, and cannot be removed without being defaced and the rollers 25 more or less marred.

My invention consists of a broad clasp, clip, or band of metal, or its equivalent, being two-thirds, more or less, of a cylinder, circular band, or ring, whose inside diameter is equal to the 30 outside diameter of the roller upon which it is to be used, and which may be the segment either of a simple ring of metal or its equivalent or of a band of suitable width. The clips are beveled on the inside edges, so as to slip 35 on easily over the fabric, which is first placed on the roller, to hold the fabric without wearing or defacing it.

In the accompanying drawings, in which similar letters of reference indicate like parts, 40 Figure 1 is a perspective view of my improved attachment. Fig. 2 is a similar view of one of the clips, showing the beveled inside edges. Fig. 3 is an end view, showing the mode of applying the clip over the curtain, and in dotted lines the clip applied.

A represents the clips; B, the roller, and C the curtain or shade.

The clip is beveled on the inside, as shown

in Figs. 2 and 3, D D being the beveled ends and E E the beveled sides, the beveling preventing the clip from cutting into the material when moved sidewise.

50 My clip is applied as follows: Upon the roller B lay the curtain C, then slip one of the clips A over both curtain and roller, about the center thereof, allowing the curtain to hang free. If it does not hang true and even, it may be made to hang so by taking hold of either free corner of the curtain and working it around the clip, as on a pivot. When satisfactorily adjusted 55 put on as many additional clips as may be necessary. The beveled edges of the clips permit their position to be shifted at pleasure by sliding them along the roller over the curtain, and also allow them to be readily slipped on 60 or off without ruffling or tearing the cloth or fabric. If the curtain or shade be of unusual weight, or subject to great strain, as the drop or scene curtain of a theater, it may be rolled once around the roller before putting on the 65 first clip. The clips will then cover the meeting portions of the curtain or shade, thereby holding it more firmly.

To remove the curtain or shade the clips are taken hold of between the thumb and forefinger and pulled off from the roller.

70 These clips, as hereinbefore described, and being of suitable size and strength, are designed and intended for use with and upon rollers and curtains of whatever size, weight, 75 or material, and for whatever purpose used.

Having thus described my invention, the following is what I claim as new therein and desire to secure by Letters Patent:

1. A broad clip, A, adapted to be applied 80 over a curtain already in position on the roller, substantially as set forth.

2. A broad clip, A, having beveled inside edges and ends, E D, adapted to be applied 85 over and to be shifted sidewise on a curtain and its roller, as set forth.

CHARLES C. MOSHER.
